E. L. THOMPSON,
AUTOMATIC CHEMICAL FIRE EXTINGUISHING APPARATUS,
APPLICATION FILED JAN. 24, 1914.

1,287,794.

Patented Dec. 17, 1918.

UNITED STATES PATENT OFFICE.

EVERETT L. THOMPSON, OF DOVER, NEW JERSEY, ASSIGNOR TO SYPHO-CHEMICAL SPRINKLER CORPORATION, OF CROTON-ON-HUDSON, NEW YORK, A CORPORATION OF NEW YORK.

AUTOMATIC CHEMICAL FIRE-EXTINGUISHING APPARATUS.

1,287,794.

Specification of Letters Patent.

Patented Dec. 17, 1918.

Application filed January 24, 1914. Serial No. 814,033.

To all whom it may concern:

Be it known that I, EVERETT L. THOMPSON, a citizen of the United States, and resident of Dover, Morris county, New Jersey, have made a certain new and useful Invention Relating to Automatic Chemical Fire-Extinguishing Apparatus, of which the following is a specification, taken in connection with the accompanying drawing, which 10 forms part of the same.

This invention relates especially to automatic fire extinguishing apparatus in which the distributing system may comprise automatic sprinkler heads, hose connections or other distributing devices and be connected with a supply tank or other supply of extinguishing liquid to be discharged from the system under suitable pressure. Under 15 emergency conditions when the liquid is discharged from the sprinkler system its flow therethrough acts through suitable Venturi or other flow actuating devices to operate any desired emergency or control devices by which a supplemental supply of extinguishing liquid may be supplied to the system as by the operation of a chemical supply tank. 20

The accompanying drawing shows in a somewhat diagrammatic way illustrative embodiments of this invention in elevation, 25 parts being shown in section.

The distributing system may be of any desired form and may as indicated comprise one or more suitable supply pipes or risers 1 and connected distributing pipes, such as 30 2, upon which automatic sprinkler heads or other distributing devices 3 may be arranged at suitable intervals. The distributing system may also comprise other distributing devices such as the hose connections 52 to 40 which hose lines may be connected and operated when the corresponding valves are opened. The distributing system may have connected therewith any suitable primary supply of extinguishing liquid, such as 45 water or a suitable solution of substantially inert soluble salts to reduce the freezing point of the liquid for the low temperature service. If desired, a primary supply tank 12 of the air pressure or gravity type may 50 be connected to the distributing system, preferably through a suitable shut-off valve 9 and check valve 64 so as to supply water or other extinguishing liquid to the various

parts of the system, the tank being so arranged if desired that it places the system 55 under full working pressure.

Under emergency conditions when some of the automatic sprinkler heads open or when the other distributing devices are brought into play the escape of extinguishing liquid causes a flow through the supply pipe or other parts of the distributing system adjacent the connected or primary supply and this flow of liquid can be utilized by means of a Venturi, jet, or other flow 60 actuating device to actuate a suitable emergency or control device and bring into action a chemical supply tank or other supplemental liquid supply so as to supply additional extinguishing liquid to the distributing 65 system or operate suitable alarm devices, or both. Any suitable form of flow actuating device operating by the flow of liquid may be used, such for example as the Venturi device which is known and used in various 70 connections to detect or measure the flow of water or other liquids, various arrangements being referred to, for instance, in the Thompson Patent No. 734,049, of November 3, 1903. In the arrangement diagrammatically 75 shown in the drawing the Venturi actuating device is arranged in a suitable by-pass connected around the upper portion 4 of one of the supply pipes of the distributing system in which a suitable check valve 6 may be 80 arranged in the chamber 5 so as to be normally held closed by the spring 7 which forces it against its seat 8 and gives it a slight differential action which may be as much as one or two pounds per square inch, 85 if desired. The pipe 13 which forms part of this by-pass may be provided with the nozzle or jet 14 and the co-operating substantially aligned jet 16 on the by-pass pipe 15 may also be arranged within the suction or Venturi 90 chamber 63. By this arrangement when flow occurs in the connected distributing system the differential check valve tends to cause the first flow of liquid to take place around the by-pass through the Venturi device 95 therein so as to cause by this Venturi or jet action a suction or relative reduction of pressure within the Venturi chamber 63 to which a suitable emergency or control device may be connected in any desired way. 100

As indicated the emergency device may

comprise the control chamber or pressure chamber 24 with which the movable control or diaphragm member 25 coöperates so as to be normally under considerable pressure 5 from the distributing system and on pressure reduction to move by its resiliency, and also aided if desired by a suitable spring, such as 35, which may coöperate with this diaphragm member in any way as by engag- 10 ing with a flange 34 on the control stem 36 connected thereto. Any suitable actuating connection may be used between this emergency device and the Venturi jet actuating device, such, for example, as the actuating 15 connection or pipe 10 communicating with the control chamber and having, if desired, the cut-off valve 11 therein.

If desired another liquid supply may be used in connection with the distributing system in addition to or instead of the pressure or gravity tank, and a city water supply or other supply of liquid under pressure may be used in this connection. The secondary supply pipe 51, for example, may be connected to the distributing system in any desired way and may be used to supply there- 20 to city water under suitable pressure either instead of or in connection with the primary supply tank of the pressure or gravity type 25 previously referred to. It is desirable especially where both these supplies are simultaneously connected to the distributing system to arrange a suitable check valve 59 in the secondary supply pipe and a similar 30 check valve 64 in the primary supply pipe, both opening inward toward the distributing system. The secondary supply pipe may also be provided with a shut-off valve 48 so that in this way either one of these liquid 35 supplies may be used separately. As shown in the drawing, a generally similar flow actuating device of the jet or Venturi type may be used in connection with this secondary supply pipe, so that in the event of flow 40 therethrough when the distributing system comes into emergency action a suitable pressure reduction or suction actuation will take place so as to operate any connected emergency devices. The Venturi device may be 45 arranged in a suitable by-pass around the supply pipe check valve 49 in this secondary supply pipe 51, this check valve being normally held closed by a spring 50 which produces a slight differential action. The Ven- 50 turi device arranged as indicated in the by- 55 pass around this check valve may comprise the substantially alined nozzles 45, 46 ar- ranged in the Venturi or suction chamber 44 so that when flow of liquid first occurs 60 through this secondary supply pipe the flow tends to take place through this by-pass Ven- turi device so as to cause in the Venturi cham- 65 ber a comparative suction or pressure re- duction, so that it may be used to operate any emergency or control device of the general

character described. If desired, such a pressure chamber control device as described may be simultaneously connected to several such Venturi actuating devices, the actuating connection or pipe 43 in which the cut-off valve 62 is preferably arranged serving to connect the Venturi chamber 44 with the control chamber 24. Under these circumstances, however, it is desirable in some cases to interpose suitable check valves in these actuating 70 connections and the check valves 19, 20 may be installed therein, preferably adjacent the control chamber so as to open and allow liquid to flow therefrom as indicated by the arrows. In order to take care of incidental 75 expansion or other slight flow of a less character than the emergency actuating movements of liquid through these actuating connections, it is sometimes desirable to have suitable equalizing connections around these 80 control check valves and for this purpose the equalizing connection 17 may be arranged around the control check valve 19 so as to normally give a pin-hole or small area equalizing passage around the same as controlled 85 by the adjustable needle valve 18 or the like and allow slow equalizing movements of liquid around this check valve in either direction between the actuating connection or pipe 10 and its extension 22. The adjustable 90 small area or pin hole equalizing connection 21 may be similarly arranged around the control check valve 20 between the actuating connection 43 and its extension 23 adjacent the control chamber 24.

The emergency devices may be used to supply to the distributing system additional extinguishing liquid under fire conditions, and for this purpose the emergency device may be arranged to put in operation a 105 chemical supply tank so as to give a specially high pressure discharge of extinguishing liquid for a short time so as to be still more effective for extinguishing purposes during the initial stages. The chemical 110 mixing tank 38 may have any suitable capacity and construction and may contain carbonate solution 42 to the desired extent, any suitable chemical mixing devices being arranged so as to mix or combine the soda 115 with the acid and secure by resulting chemi- 120 cal action the desired high pressure in this tank. These mixing devices may comprise a tipping acid container 37 which may be actuated in any way from the control device 125 as by having its upper end engaged by the control stem 36 so that when the emergency or control device operates so as to move this stem upward the acid container is released and the acid discharged therefrom in the desired way to produce the high chemically generated gas pressure and force the liquid out of this chemical supply tank through a suitable connection at pressures as great as several hundred pounds per square inch, 130

if desired. The chemical supply tank may with advantage be connected with the distributing system through an automatic venting connection which may comprise the 5 depending end 27 of this connection with the supply tank which may have a lower end 39 adjacent the tank bottom. A suitable check or automatic stop valve 26 is preferably arranged in this venting connection to prevent liquid from the distributing system entering the chemical supply tank and between the check valve and the liquid level in the chemical supply tank a suitable venting drain device may be arranged 10 so as to discharge any leakage of liquid from the distributing system or otherwise vent any air or other pressure developed. This venting drain device, such as 60, may comprise a suitable chamber with 15 which cooperates a venting float valve 41 which is preferably normally open so as to give at least a small opening at this point while it is automatically closed by the connected float 40 as soon as liquid enters this 20 part of the connection. A suitable air escape venting aperture 61 may also be provided in this connection between the check valve and liquid level and preferably within the tank adjacent its upper portion as indicated 25 so as to give a pin-hole or small area air venting opening at this point. It is desirable to have emergency supply tank devices when operated by chemically generated or other pressure arranged so that 30 when the liquid in the tank has been substantially discharged into the distributing system at the desired increased pressure further discharge from the pressure operated tank will automatically cease and any 35 further extinguishing liquid required will be supplied to the distributing system by the primary or other liquid supply devices which may produce somewhat lower pressure in the system. This can be effected, for 40 instance, by using charges of chemicals in the mixing tank of such amount that the pressure therein though under emergency conditions initially much higher than the working pressure in the system gradually 45 falls off so as to be less than the normal working pressure before all the liquid in the chemical supply tank is exhausted under which conditions the check valve between the pressure tank and distributing system 50 would automatically close. Or, if desired, more positive shut-off means may be used to accomplish this result, as for instance, a suitable shut-off valve such as 67 which may coöperate with the connection between 55 the chemical pressure supply tank and the distributing system as by being pivoted about the pin 68 and automatically operated as by being connected with the float 69. This float normally holds the shut-off 60 valve in the open position indicated in the drawing, but when the liquid level in the tank approaches the tank bottom this float which is preferably out of line with the acid container is no longer buoyed up but falls with the liquid and closes the shut-off valve 70 so as to prevent further discharge of liquid from the tank. Under these conditions if an air venting aperture has been used in this tank connection it should be closed by suitable means which may be connected to 75 the same mechanism operating the automatic shut-off valve or to any other devices such, for example, as the vent shut-off valve 65 which may be pivotally mounted adjacent the venting aperture 61 and have connected thereto the float 66 which as soon as the liquid level in the tank falls a few inches, for instance, closes this venting aperture and prevents any further escape of air or gas therethrough. 80

The emergency or control device may be arranged in connection with coöoperating devices or apparatus of any suitable description to give any desired emergency action or indication and it may be arranged to 85 actuate suitable alarm devices, such for example, as the electric alarm 30 which may be connected in circuit with the battery or other source of current 31 and with the wires 28, 29 which lead to the movable electric contact 32 and the coöoperating resilient contact 33, for example, so that when the movable contact is swung about its pivot by its engagement with the moving flange 34 of the control device these contacts are 90 swung together and the electric alarm operated until manually disengaged. 95

If desired also any suitable form of alarm may be arranged in connection with the chemical or other pressure supply tank so 100 as to be actuated by pressure therein in the event of the operation of the chemical mixing devices or the development in any other way of an abnormal or increased pressure. This alarm which may if desired be pneumatically operated by being connected to the air space in the tank may comprise any 105 form of pneumatic alarm or whistle 56 arranged at any convenient or desired point and connected with the upper air space in 110 the tank 38 by the small area pipe 55 of such size as not to unduly lower the gas pressure produced by this chemical action. For some purposes, especially where the fire is very slight and only slight discharge of 115 extinguishing liquid occurs from a hose connection, for instance, it is rather advantageous to have the gas pressure in the chemical tank relieved and this may be automatically effected by the action of such a 120 pneumatic alarm, for example. If, however, a considerable amount of the extinguishing liquid is required it is undesirable to allow very much of this gas produced by the chemical action referred to to 125 130

escape and for this reason it is desirable to use an automatic shut-off valve or device to stop the escape of fluid through this pneumatic alarm under such conditions.

- 5 The float shut-off valve 54 may be arranged for this purpose and connected with the float 53 supported in the liquid 42 in the chemical supply tank, so that when any desired portion of this liquid is drawn off 10 this shut-off valve closes and further escape of gas through the pneumatic alarm ceases, after for instance the liquid level in the tank has fallen six inches or more.

It will be understood from the foregoing 15 description that the distributing system is normally filled with water or other suitable non-freezing liquid under working pressure which is maintained by the supply tank or other source of supply and is always effec-

- 20 tive to operate the distributing devices in the system in case of fire. As soon as such emergency operation begins the resulting flow of liquid through the supply pipes or other parts of the distributing system op- 25 erates through such flow actuating devices as have been described to actuate a suitable emergency or control device which may be used not only to give an alarm of any desired character, but also to start the ac- 30 tion of a pressure supply tank which may be of the chemical mixing type, and quickly furnish to the distributing system a supplemental supply of extinguishing liquid under considerably higher pressure if desired so 35 as to have a still more effective extinguish- ing action for a considerable time, the check valves in the supply pipes connecting the distributing system to the primary supply tank or other source of extinguishing liquid

- 40 being preferably automatically shut at this time to prevent any undesirable reduction of this high chemical pressure. When the extinguishing liquid in the chemical supply tank is substantially exhausted the connec- 45 tion between this tank and the distributing system may be automatically closed so that the other liquid supplies to the system are thus allowed to instantly come into action and continue the discharge of liquid from 50 the operating distributing devices.

This invention has been described in connection with a number of illustrative embodiments, forms, elements, materials, parts and arrangements, to the details of which 55 disclosure the invention is not of course to be limited, since what is claimed as new and what is desired to be secured by Letters Patent is set forth in the appended claims.

- 60 1. In automatic sprinkler apparatus, a distributing system comprising automatic distributing devices, a primary supply tank connected to said distributing system, a supply pipe check valve in said distributing system adjacent said supply tank, a Venturi

actuating device arranged in a by-pass around said supply pipe check valve, a secondary supply pipe connected to said distributing system and having therein a secondary supply pipe check-valve and a Venturi 70 actuating device arranged in a by-pass around said secondary supply pipe check valve, an emergency device comprising a control chamber, a coöperating movable control member, actuating connections between 75 said Venturi actuating devices and said control chamber, said actuating connections each comprising a control check valve and a pin-hole equalizing connection arranged in a by-pass around said control check valve, 80 and a supplemental supply of extinguishing liquid comprising a chemical supply tank having chemical mixing devices arranged to be operated by said control member.

2. In automatic sprinkler apparatus, a 85 distributing system comprising distributing devices, a primary supply tank connected to said distributing system, a supply pipe check valve in said distributing system adjacent said supply tank, a Venturi actuating device arranged in a by-pass around said supply pipe check valve, a secondary supply pipe connected to said distributing system, said supply pipe having therein a secondary supply pipe check valve and a 90 Venturi actuating device arranged in a by- 95 pass around said secondary supply pipe check valve, an emergency device comprising a control chamber, a coöperating movable control member, and actuating connec- 100 tions between said Venturi actuating devices and said control chamber, said actuating connections each comprising a control valve.

3. In automatic sprinkler apparatus, a dis- 105 tributing system comprising distributing de- vices, a primary supply tank connected to said distributing system, a supply pipe valve in said distributing system adjacent said supply tank, a Venturi actuating device ar- 110 ranged in a by-pass around said supply pipe check valve, a secondary supply pipe connected to said distributing system and having therein a secondary supply pipe check valve and a Venturi actuating device ar- 115 ranged in a by-pass around said secondary supply pipe valve, a coöperating movable control member, and actuating connections between said Venturi actuating devices and said control chamber, said actuating connec- 120 tions each comprising a control check valve.

4. In automatic sprinkler apparatus, a dis- 125 tributing system, a primary supply connected to said distributing system, a check valve, a supply pipe valve in said distributing system adjacent said primary supply, a Venturi flow actuating device arranged in connection with said supply pipe, a second- 130 ary supply pipe connected to said distrib-

uting system and having therein a secondary supply pipe valve, a Venturi flow actuating device arranged in connection with said secondary supply pipe, an emergency device and actuating connections between said Venturi actuating devices and said control device, said actuating connections each comprising a control check valve and a pin-hole equalizing connection arranged around said

10 control check valve.

5. In automatic sprinkler apparatus, a distributing system, a primary supply connected to said distributing system, a check valve a supply pipe valve in said distributing system adjacent said primary supply, a flow actuating device arranged in connection with said supply pipe, a secondary supply pipe connected to said distributing system and having therein a secondary supply pipe valve, and a flow actuating device arranged in connection with said secondary supply pipe, an emergency device and actuating connections between said actuating devices and said emergency device, said actuating connections each comprising a control check valve.

6. In automatic sprinkler apparatus, a distributing system, a primary supply connected to said distributing system, a check valve, a flow actuating device arranged in connection with said supply pipe, a secondary supply pipe connected to said distributing system, a flow actuating device arranged in connection with said secondary supply pipe, an emergency device and actuating connections between said actuating devices and said emergency device.

7. In automatic sprinkler apparatus, a wet pipe distributing system comprising automatic distributing devices, a primary extinguishing liquid supply tank connected to said distributing system, a Venturi flow actuating device arranged in connection with said distributing system to operate on the commencement of substantial flow in said system, an emergency control device comprising a control chamber, a coöperating resilient control diaphragm, a connected control stem, an actuating connection between said actuating device and said control chamber, a chemical supply tank having chemical mixing devices comprising a tipping container arranged to be released when said control stem is operated by said actuating devices and a connection between said chemical supply tank and said distributing system comprising a check valve and an automatic venting drain device between said check valve and tank.

60. 8. In automatic sprinkler apparatus, a distributing system comprising distributing devices, a primary extinguishing liquid supply tank connected to said distributing system, a Venturi flow actuating device arranged

to operate on the commencement of substantial flow in said system, an emergency control device comprising a control chamber, a coöperating resilient control diaphragm, a connected control stem, an actuating connection between said actuating device and said control chamber, a chemical supply tank having chemical mixing devices arranged to be released when said control stem is operated by said actuating devices and a connection between said chemical supply tank and said distributing system comprising a check valve and an automatically closing venting drain device between said check valve and tank.

70 9. In automatic sprinkler apparatus, a distributing system charged with extinguishing liquid and comprising distributing devices, a primary extinguishing liquid supply tank connected to said distributing system, a jet flow actuating device arranged in connection with said distributing system to operate on the commencement of substantial flow in said system, an emergency control device comprising a control chamber, a coöperating control diaphragm, a connected control stem, an actuating connection between said actuating device and said control chamber, a chemical supply tank having chemical mixing devices arranged to be released when said control stem is operated by said actuating devices and a connection between said chemical supply tank and said distributing system.

75 10. In automatic sprinkler apparatus, a distributing system comprising automatic distributing devices, a primary extinguishing liquid supply tank connected to said distributing system, a supply pipe check valve in said distributing system adjacent said supply tank, a Venturi jet flow actuating device arranged in a by-pass around said supply pipe check valve, an emergency control device comprising a movable control member, an actuating connection between said actuating device and said control device chamber, a supplemental chemical supply tank having chemical mixing devices arranged to be operated when said control device is operated by said actuating device and a connection between said chemical supply tank and said distributing system comprising a check valve and an automatic venting drain device between said check valve and tank.

80 11. In automatic sprinkler apparatus, a distributing system comprising distributing devices, a primary extinguishing liquid supply connected to said distributing system, a supply pipe check valve in said distributing system adjacent said supply, a Venturi jet flow actuating device arranged in a by-pass around said supply pipe check valve, an emergency control device comprising a movable control member, an actuating connec-

tion between said actuating device and said control device chamber, a supplemental chemical supply tank having chemical mixing devices arranged to be operated when 5 said control device is operated by said actuating device and a connection between said chemical supply tank and said distributing system.

12. In automatic sprinkler apparatus, a 10 distributing system comprising distributing devices, a primary extinguishing liquid supply comprising a tank connected adjacent the top of said distributing system, a supply pipe check valve in said distributing system 15 adjacent said supply, a jet flow actuating device arranged in a by-pass around said supply pipe check valve, an emergency control device comprising a movable control member, an actuating connection between 20 said actuating device and said control device, a connected chemical supplemental supply tank arranged to be operated when said control device is operated by said actuating device, and a connection between said chemical 25 supply tank and said distributing system. 90

13. In automatic sprinkler apparatus, a distributing system comprising distributing devices, a primary extinguishing liquid supply 30 connected to said distributing system, a Venturi jet flow actuating device arranged in connection with said distributing system to be operated by flow therethrough, and a supplemental extinguishing fluid supply 35 comprising a chemical pressure supply tank having chemical mixing devices arranged to be operated by said actuating device. 95

14. In automatic sprinkler apparatus, a distributing system comprising distributing 40 devices, a primary extinguishing liquid supply connected to said distributing system, a jet flow actuating device arranged in connection with said distributing system to be operated by flow therethrough and a supplemental extinguishing fluid supply comprising a supply tank arranged to be operated 45 by said actuating device. 100

15. In automatic sprinkler apparatus, a distributing system charged with extinguishing 50 liquid and comprising distributing devices, a primary extinguishing liquid supply connected to said distributing system, a jet flow actuating device arranged in connection with said distributing system to be operated by flow therethrough and a supplemental extinguishing fluid supply arranged to be operated 55 by said actuating device. 110

16. In automatic fire extinguishing apparatus, a distributing system normally charged 60 with extinguishing liquid and comprising automatic sprinkler heads and hose distributing devices, a primary supply of extinguishing liquid comprising a supply tank connected to a supply pipe of said distributing 65 system to maintain effective pressure 125

therein, a Venturi flow actuating device co-operating with said supply pipe to cause a reduction pressure change on the beginning of flow through said supply pipe under emergency conditions, a supplemental supply of extinguishing liquid comprising a chemical pressure supply tank, an automatically closing venting connection between said pressure supply tank and said distributing system, chemical mixing devices in 70 said tank, means connected to said actuating device to operate said mixing devices, an automatic shut-off valve in said pressure supply tank and a connected float in said tank to automatically close said connection 75 and shut off discharge into the distributing system when the liquid in said tank approaches exhaustion, a pneumatic alarm connected to the air space of said tank to give an alarm by pneumatic pressure from said 80 tank under emergency conditions and a float shut-off valve in said tank to stop escape of pressure through said alarm when the liquid in said tank is exhausted to the desired extent. 90

17. In automatic fire extinguishing apparatus, a distributing system normally charged with extinguishing liquid and comprising distributing devices, a primary supply of extinguishing liquid connected to a 95 supply pipe of said distributing system to maintain effective pressure therein, a flow actuating device co-operating with said supply pipes to cause a pressure change on the beginning of flow through said supply pipe 100 under emergency conditions, a supplemental supply of extinguishing liquid comprising a chemical pressure supply tank, an automatic venting connection between said pressure supply tank and said distributing system, chemical mixing devices in said tank, means connected to said actuating device to operate said mixing devices, a pneumatic alarm connected to the air space of said tank to give an alarm by pneumatic pressure from said tank under emergency conditions and a float shut-off valve in said tank to stop escape of pressure through said alarm when the liquid in said tank is exhausted to the desired extent. 110 115

18. In automatic fire extinguishing apparatus, a distributing system normally charged with extinguishing liquid and comprising distributing devices, a primary supply of extinguishing liquid connected to a 120 supply pipe of said distributing system to maintain effective pressure therein, a jet flow actuating device co-operating with said supply pipe to cause a pressure change on the beginning of flow through said supply pipe 125 under emergency conditions, a supplemental supply of extinguishing liquid comprising a chemical pressure supply tank, a connection between said pressure supply tank and said distributing system, chemical mixing 130

devices in said tank, and means connected to said control member to operate said mixing devices.

19. In automatic fire extinguishing apparatus, a distributing system comprising distributing devices, a primary supply of extinguishing liquid connected to a supply pipe of said distributing system, a jet flow actuating device coöperating with said supply pipe to cause a pressure change on the beginning of flow through said supply pipe under emergency conditions, a supplemental supply of extinguishing liquid comprising a chemical pressure supply tank, a connection between said pressure supply tank and said distributing system, chemical mixing devices in said tank, and means connected to said control member to operate said mixing devices.

20. In automatic fire extinguishing apparatus, a wet pipe distributing system comprising automatic distributing devices, a primary supply of extinguishing liquid comprising a supply tank connected to a supply pipe of said distributing system to maintain normal working pressure therein, a Venturi jet flow actuating device coöperating with said supply pipe to cause a reduction pressure change on the beginning of flow of liquid through said supply pipe under emergency conditions, a supplemental supply of extinguishing liquid comprising a chemical pressure supply tank, an automatic venting connection between said supplemental supply and said distributing system, chemical mixing devices in said tank and means coöperating with said actuating device to operate said supplemental supply.

21. In automatic fire extinguishing apparatus, a wet pipe distributing system comprising distributing devices, a primary supply of extinguishing liquid connected to a supply pipe of said distributing system to maintain normal working pressure therein, a Venturi jet flow actuating device coöperating with said supply pipe to cause a reduction pressure change on the beginning of flow of liquid through said supply pipe under emergency conditions, a supplemental supply of extinguishing liquid comprising a pressure supply tank, a connection between said supplemental supply and said distributing system, chemical mixing devices in said tank, and means coöperating with said actuating device to operate said supplemental supply.

22. In automatic fire extinguishing apparatus, a distributing system comprising distributing devices, a primary supply of extinguishing liquid connected to a supply pipe of said distributing system, a Venturi jet flow actuating device coöperating with said supply pipe to cause a reduction pressure change on the beginning of flow of liquid through said supply pipe under emergency conditions, a supplemental supply of extinguishing liquid comprising a chemical pressure supply tank, an automatic venting connection comprising a check valve between said pressure supply tank and said distributing system comprising an air venting aperture communicating with said tank adjacent the upper portion thereof, a vent shut-off valve coöperating with said aperture, a valve and connected float to automatically close said aperture when the liquid level descends in said tank, chemical mixing devices in said tank comprising a tipping acid container, control means connected to said control member to operate said mixing devices, and an automatic shut-off valve in said pressure supply tank and a valve and

gency conditions, a supplemental supply of extinguishing liquid comprising a pressure tank, a connection between said supplemental supply and said distributing system, chemical mixing devices in said tank and means coöperating with said actuating device to operate said supplemental supply.

23. In automatic fire extinguishing apparatus, a distributing system comprising distributing devices, a primary supply of extinguishing liquid connected to a supply pipe of said distributing system, a jet flow actuating device coöperating with said supply pipe to cause a reduction pressure change on the flow of liquid through said supply pipe under emergency conditions, a supplemental supply of extinguishing liquid comprising a pressure tank, a connection between said supplemental supply and said distributing system, chemical mixing devices in said tank and means coöperating with said actuating device to operate said supplemental supply.

24. In automatic fire extinguishing apparatus, a distributing system comprising distributing devices, a primary supply of extinguishing liquid connected to a supply pipe of said distributing system, a jet flow actuating device coöperating with said supply pipe to cause a pressure change on the flow of liquid through said supply pipe under emergency conditions, a supplemental supply of extinguishing liquid comprising a pressure tank, a connection between said supplemental supply and said distributing system, chemical mixing devices in said tank and means coöperating with said actuating device to operate said supplemental supply.

25. In automatic fire extinguishing apparatus, a distributing system normally charged with extinguishing liquid and comprising automatic distributing devices, a primary supply of extinguishing liquid comprising a supply tank connected to a supply pipe of said distribution system to normally maintain effective liquid pressure therein, a connected emergency device comprising a control member actuated under emergency conditions of the system, a supplemental supply of extinguishing liquid comprising a chemical pressure supply tank, an automatic venting connection comprising a check valve between said pressure supply tank and said distributing system comprising an air venting aperture communicating with said tank adjacent the upper portion thereof, a vent shut-off valve coöperating with said aperture, a valve and connected float to automatically close said aperture when the liquid level descends in said tank, chemical mixing devices in said tank comprising a tipping acid container, control means connected to said control member to operate said mixing devices, and an automatic shut-off valve in said pressure supply tank and a valve and

- connected float in said tank to automatically close said connection and shut off discharge from said tank into the distributing system when the liquid in said tank approaches exhaustion.
26. In automatic fire extinguishing apparatus, a distributing system normally charged with extinguishing liquid and comprising automatic distributing devices, a primary supply of extinguishing liquid connected to a supply pipe of said distributing system to normally maintain effective liquid pressure therein, a connected emergency device comprising a control member actuated under emergency conditions of the system, a supplemental supply of extinguishing liquid comprising a chemical pressure supply tank, an automatic venting connection comprising a check valve between said pressure supply tank and said distributing system comprising an air venting aperture in said tank adjacent the upper portion thereof, a vent shut-off valve coöperating with said aperture, a connected float to automatically close said aperture when the liquid level descends in said tank, chemical mixing devices, control means connected to said control member to operate said mixing devices, and an automatic shut-off valve in said pressure supply tank and a connected float in said tank to automatically close said connection and shut off discharge from said tank into the distributing system when the liquid in said tank approaches exhaustion.
27. In automatic fire extinguishing apparatus, a distributing system normally charged with extinguishing liquid and comprising automatic distributing devices, a primary supply of extinguishing liquid connected to a supply pipe of said distributing system, a connected emergency device comprising a control member actuated under emergency conditions of the system, a supplemental supply of extinguishing liquid comprising a chemical pressure supply tank, a connection between said pressure supply tank and said distributing system, chemical mixing devices, control means connected to said control member to operate said mixing devices, and an automatic shut-off valve in said pressure supply tank and a connected float in said tank to automatically close said connection and shut off discharge from said tank into the distributing system when the liquid in said tank approaches exhaustion.
28. In fire extinguishing apparatus, a distributing system, a connected chemical liquid supply tank and connected means to automatically create a high pressure in said tank under emergency conditions of the system and discharge liquid from said tank into the system, a pressure relief device connected to the air space of said tank and means comprising a float to close said relief device and stop further reduction of pressure there-
- through when the liquid in said tank is exhausted to the desired extent.
29. In fire extinguishing apparatus, a distributing system, a connected supplemental supply of extinguishing liquid comprising a chemical pressure tank, chemical mixing devices coöperating with said tank and automatically operating on the emergency condition of said system and a venting connection communicating with the outside air and connected to the air space of said tank and means to automatically close said venting connection when a portion of the liquid in said tank has been withdrawn.
30. In fire extinguishing apparatus, a distributing system, a connected supplemental supply of extinguishing liquid comprising a gaseous pressure tank automatically operating on the emergency condition of said system and a pressure relief device connected to the air space of said tank and means to automatically close said relief device when a portion of the liquid in said tank has been withdrawn.
31. In fire extinguishing apparatus, a distributing system containing extinguishing liquid and comprising automatic sprinkler heads and hose connection distributing devices, a connected emergency device, a supplemental supply of extinguishing liquid comprising a chemical supply tank and chemical mixing devices operated by said emergency device and a venting connection between said chemical supply tank and said distributing system, a check valve between said system and said venting connection and an air escape venting aperture for the air space in said tank located in said connection between said check valve and said liquid level.
32. In fire extinguishing apparatus, a distributing system containing extinguishing liquid and comprising distributing devices, a connected emergency device, a supplemental supply of extinguishing liquid comprising a chemical supply tank and chemical mixing devices operated by said emergency device and an automatic venting connection opening into the outer air between said chemical supply tank and said distributing system.
33. In fire extinguishing apparatus, a distributing system containing extinguishing liquid and comprising automatic sprinkler distributing devices, a connected emergency device, a supplemental supply of extinguishing liquid comprising a supply tank operated by said emergency device and an automatic venting connection opening into the outer air between said chemical supply tank and said distributing system.
34. In fire extinguishing apparatus, a distributing system comprising automatic sprinkler heads and hose connection distributing devices, a connected emergency device comprising a control chamber, a supplemen-

tal supply of extinguishing liquid comprising a chemical supply tank and chemical mixing devices operated by said emergency device and a venting connection between said tank and said distributing system comprising a check valve and a depending portion communicating with said tank adjacent the bottom thereof and below the normal liquid level therein, a venting drain device comprising a normally open drain aperture and a coöperating float valve communicating with said connection between said check valve and said liquid level.

35. In fire extinguishing apparatus, a distributing system comprising automatic sprinkler heads, a connected emergency device comprising a chemical supply tank and chemical mixing devices operated under emergency conditions and a venting connection between said tank and said distributing system comprising a check valve and a depending portion communicating with said tank adjacent the bottom thereof and below the normal liquid level therein, a venting drain device comprising a normally open drain aperture and a coöperating float valve communicating with said connection between said check valve and said liquid level.

36. In fire extinguishing apparatus, a distributing system, a chemical supply tank and chemical mixing devices and a venting connection between said tank and said distributing system comprising a check valve and a depending portion communicating with said tank adjacent the bottom thereof and below the normal liquid level therein, a venting drain device comprising a normally open drain aperture and a coöperating float valve communicating with said connection between said check valve and said liquid level, and an air escape venting aperture for the air space in said tank in said connection between said check valve and said liquid level.

37. In fire extinguishing apparatus, a distributing system, a chemical supply tank and chemical mixing devices and a venting connection between said tank and said distributing system comprising a check valve and a portion communicating with said tank below the normal liquid level therein, a venting drain device comprising a normally open drain aperture and a coöperating float valve communicating with said connection between said check valve and said liquid level.

38. In fire extinguishing apparatus, a distributing system, a chemical supply tank and chemical mixing devices and a venting

connection between said tank and said distributing system comprising a check valve and a portion communicating with said tank below the normal liquid level therein, a venting drain device comprising a drain aperture and a coöperating automatic valve communicating with said connection between said check valve and said liquid level.

39. In fire extinguishing apparatus, a wet pipe distributing system comprising stationary distributing devices, a pressure operated chemical supply tank and chemical mixing devices operated automatically on the emergency condition of said distributing system and an automatic venting connection between said tank and said distributing system comprising a check valve and a depending portion communicating with said tank adjacent the bottom thereof and below the normal liquid level therein, a venting drain device comprising a normally open drain aperture and a coöperating float valve communicating with said connection between said check valve and said liquid level and an air escape venting aperture for the air space in said tank in said connection between said check valve and said liquid level.

40. In fire extinguishing apparatus, a distributing system comprising stationary distributing devices, a pressure operated supply tank operated automatically on the emergency condition of said distributing system and an automatic venting connection between said tank and said distributing system comprising a check valve and a portion communicating with said tank below the normal liquid level therein, a venting drain device comprising a normally open drain aperture and a coöperating float valve communicating with said connection between said check valve and said liquid level and an air escape venting aperture for the air space in said tank in said connection between said check valve and said liquid tank.

41. In fire extinguishing apparatus, a distributing system comprising distributing devices, a pressure operated supply tank operated on the emergency condition of said distributing system and an automatic venting connection between said tank and said distributing system comprising a valve and a portion communicating with said tank below the normal liquid level therein, a venting drain device comprising a normally open drain aperture and a coöperating automatically closing valve communicating with said connection between said valve and said liquid level.

42. In fire extinguishing apparatus, a distributing system comprising distributing devices, a pressure operated supply tank operated on the emergency condition of said distributing system and an automatic venting connection between said tank and said distributing system comprising a valve and

a portion communicating with said tank below the normal liquid level therein, a venting device comprising an aperture connected with the outside air and a coöperating automatically closing valve communicating with said connection between said valve and said liquid level.

43. In fire extinguishing apparatus, a distributing system comprising distributing devices, a connected emergency device, a supply of extinguishing liquid comprising a pressure operated chemical supply tank operated by said emergency device and an automatic venting connection between said tank and said distributing system comprising a shut-off valve and a venting drain device comprising a normally open drain aperture connected with the outside air and a coöperating automatically closing valve communicating with said connection between said shut-off valve and the liquid level in said tank.

44. In fire extinguishing apparatus, a distributing system comprising distributing devices, a connected emergency device, a supply of extinguishing liquid comprising a pressure operated supply tank operated by said emergency device and an automatically closing venting connection between said tank and said distributing system and communicating with the outside air.

45. In fire extinguishing apparatus, a distributing system comprising distributing devices, a supply of extinguishing liquid comprising a pressure operated supply tank and an automatically closing venting connection between said tank and said distributing system communicating with the outside air.

46. In automatic fire extinguishing apparatus, a distributing system normally charged with extinguishing liquid and comprising automatic distributing devices, a primary supply of extinguishing liquid connected to a supply pipe of said distributing system to maintain effective pressure therein, a supplemental supply of extinguishing liquid comprising a chemical pressure supply tank, an automatic venting connection between said pressure supply tank and said distributing system, chemical mixing devices coöperating with said tank, a pneumatic alarm whistle connected to the air space of said tank to give an alarm by pneumatic pressure from said tank under abnormal pressure conditions and a float shut-off valve in said tank to stop loss of pressure through said alarm when the liquid in said tank is exhausted to the desired extent.

47. In fire extinguishing apparatus, a distributing system, a supplemental supply of extinguishing liquid comprising a chemical pressure supply tank, a venting connection between said pressure supply tank and said distributing system, chemical mixing devices coöperating with said tank, a pneumatic alarm whistle connected to the air space of said tank to give an alarm by pneumatic pressure from said tank under abnormal pressure conditions and a float shut-off valve in said tank to stop loss of pressure through said alarm when the liquid in said tank is exhausted to the desired extent.

48. In fire extinguishing apparatus, a distributing system, a supplemental supply of extinguishing liquid comprising a pressure supply tank, a connection between said pressure supply tank and said distributing system, a pneumatic alarm whistle connected to the air space of said tank to give an alarm by pneumatic pressure from said tank under abnormal pressure conditions and a float shut-off valve in said tank to stop loss of pressure through said alarm when the liquid in said tank is exhausted to the desired extent.

49. In fire extinguishing apparatus, a distributing system, a supplemental supply of extinguishing liquid comprising a pressure supply tank, a connection between said pressure supply tank and said distributing system, a pneumatic alarm connected to the air space of said tank to give an alarm by pneumatic pressure from said tank under abnormal pressure conditions and a float shut-off valve in said tank to stop loss of pressure through said alarm when the liquid in said tank is exhausted to the desired extent.

50. In automatic fire extinguishing apparatus, a distributing system comprising distributing devices, a primary supply of extinguishing liquid connected to a supply pipe of said distributing system, a Venturi jet flow actuating device coöperating with said supply pipe to cause a reduction pressure change on the beginning of flow of liquid through said supply pipe under emergency conditions, a supplemental supply of extinguishing liquid comprising a chemically generated fluid pressure tank, a connection between said supplemental supply and said distributing system, and chemical mixing devices in said tank.
